UNITED STATES PATENT OFFICE.

JOHN SPLITDORF, OF NEW YORK, N. Y.

INDUCTION-COIL.

No. 812,607.

Specification of Letters Patent.

Patented Feb. 13, 1906.

Application filed November 15, 1904. Serial No. 282,890.

To all whom it may concern:

Be it known that I, JOHN SPLITDORF, a citizen of the United States, residing at New York city, in the county of New York and State of New York, have invented a new and useful Improvement in Induction-Coils, of which the following is a specification.

My invention relates to improvements in induction-coils in which a soft iron core is magnetized by a current of electricity and demagnetized by breaking the electric circuit to create magnetic lines of force that cut the convolutions of a secondary coil of wire wound about the soft iron core and the wire through which the current passes to produce a secondary current of high tension; and the object of my invention is to prevent the heating of the soft iron core. In all electromagnetic coils the very rapid magnetization and demagnetization of the iron core causes the iron to become quite hot, and this heat is detrimental to the insulation used between the coils as well as impairs the efficiency of the apparatus.

I attain my object by the mechanism illustrated in the accompanying drawings, in which—

Figure 1 is a vertical section of an ordinary induction-coil. Fig. 2 is a horizontal section of the same. Fig. 3 is a vertical section of an enlarged iron core separated from the coil, showing apertures extending through the iron; and Fig. 4 is a top view of Fig. 3.

Similar numbers refer to similar parts throughout the several views.

In Fig. 1 the numeral 1 represents a soft iron core supported by the square frames 10. 2 is an iron armature rigidly attached to the flat spring 11, which is supported by the bearing 15. 3 represents a thumb-screw with a jam-nut capable of adjustment upon the frame 16. 4 represents the contact-point between the spring 11 and the thumb-screw 3. 6 indicates a secondary winding of fine wire. 7 indicates the primary winding of coarse wire, separate from the core 1 and the primary winding 6 by the insulating material 8. 12 represents an open space between the core 1 and the insulating material 8, and 9 represents apertures through the

frames 10, connecting the open space 12 with the external atmosphere.

In Fig. 3, 14 is an enlarged view of an iron core, showing the apertures 13 extending through its length to allow the free passage of the atmosphere.

In Fig. 4, 13 and 5 indicate the apertures extending through the iron core 14.

In ordinary induction-coils one end of the primary coil 7 is connected with the spring 6 or 11 at the bearing 15 and the other end to one pole of the source of electricity, while the second pole is connected with the thumb-screw 3 by means of the bearing 16. When the spring 11 makes a contact with the thumb-screw 3 at the point 4, the current of electricity passes through the primary coil 7 and magnetizes the iron core 1. The moment this core 1 is magnetized the armature 2 is attracted toward the core and the contact at 4 is broken. In breaking the contact at 4 the electric circuit is disrupted, then the iron core loses its magnetism, and the spring 11 flies back until it meets the thumb-screw 3 and closes the contact at 4. This operation is repeated very rapidly, and the rapid magnetization and demagnetization of the core causes the iron in the core to become hot and injurious to the coil. By means of my invention I cause a free circulation of air about and through the core, which eliminates the heat and keeps the core cool, thus increasing the efficiency of the coil and preventing any injury to the insulation.

What I claim as my invention, and desire to secure by Letters Patent, is—

1. A casing or container for an induction-coil, having apertures through its walls extending from an air-space about the iron core to the outer atmosphere.

2. In an induction coil inclosed in a casing or container, whose iron core is separated from the primary winding by an air-space, the iron core projecting beyond the walls of the container and the apertures 9 extending through the container from the air-space 12.

3. In an induction-coil, the combination with the primary and secondary windings, of a ventilated iron core, consisting of an open space around the core, and one or more apertures 100

tures extending through the core; substantially as described.

4. In an electromagnet, means for ventilating the iron core, consisting of an open space around the core, and one or more apertures extending through the core; substantially as described.

In testimony whereof I have signed my

name to this specification, in the presence of two subscribing witnesses, this 1st day of 10 November, 1904.

JOHN SPLITDORF.
